[57] ABSTRACT

A new and distinct cultivar of impatiens plant named Barbados, characterized by its large, bright orange flowers, compact growth habit with excellent self-branching without pinching, medium green foliage with reddish midveins, very early and uniform flowering, floriferous habit, and by its suitability to pot or hanging basket culture.

1 Drawing Sheet

1

The present invention relates to a new and distinct cultivar of plant known as impatiens and commercially known as New Guinea impatiens. The new cultivar is known by the cultivar name Barbados, and was developed by the inventor Ludwig Kientzler in Gensingen, Federal Republic of Germany by crossing the cultivar designated D-191 (seed parent) with the cultivar designated D-224 (pollen parent).

Asexual reproduction by terminal (stem tip) cuttings taken by me or under my supervision at Gensingen, Federal Republic of Germany, has shown that the unique features of this new impatiens are stabilized and are reproduced true to type in successive propagations.

The following characteristics distinguish the new impatiens from both its parent varieties and other cultivars of this general type known and used in the floriculture industry:

1. Compact growth habit, yet fast growing and self-branching to give a full appearance. Growth upright. Plants in 16.5 cm pots were 18 cm tall and 30 cm wide, eight weeks after planting.
2. Large, bright orange flowers. Open flowers measure up to 6 cm in diameter.
3. Early flowering and very floriferous. Plants in 16.5 cm pots were in flower 6 weeks after planting.
4. Medium green foliage with a reddish midvein on the proximal half of the leaf blade.
5. Well suited both to 4" pot and 8" hanging basket culture.

The flower color of Barbados is most similar to the flower color of Antigua, although the color of Barbados is a lighter, brighter orange. Flowering of Barbados is at least one week earlier than Antigua, and the habit is more upright. Antigua is a cultivar of applicant disclosed in a pending application.

The accompanying colored photograph is a top perspective view of the new cultivar, showing color as true as it is reasonably possible to obtain in a colored reproduction of this type.

The following is a detailed description of my new impatiens cultivar based on plants grown under commercial practice in Encinitas, Calif. Plants were started as rooted cuttings and were transplanted in mid-December into 16.5 cm (6.5 inch) pots, one pot per plant. By mid-February, plants were growing vigorously and were in flower. The values, measurements and observa-

2

tions noted below were taken from plants in full bloom in mid-February.

Color references are made to The Royal Horticultural Society Colour Chart (R.H.S.), except where general terms of ordinary dictionary significance are used.

Parentage: Cross between D-191 (seed) and D-224 (pollen).

Asexual reproduction:

- A. Cutting type.—Tip, with stems 2-3 cm long developing to 4-5 cm after 21 days in propagation.
- B. Time to initiate roots.—8-10 days at 23° C.; nicely developed root mass in 18-21 days.
- C. Rooting habit.—Numerous, fibrous, adventitious roots from the stem.

Plant description:

- A. Form.—Symmetrical, bush shaped, flowering herb, with self-branching characteristics giving the plant a full appearance. Pinching is not recommended since it does not enhance branching and only delays flowering by removing flower buds.
- B. Habit of growth.—Vigorous, self-branching habit, producing whorls of leaves and flowers. Growth is indeterminate and flowering is continuous.

- C. Foliage description.—Leaves are simple. Lower leaves on stems are opposite. Higher leaves in whorls of 3-5, but predominately 5. 1. Leaf shape: Broadly lanceolate to somewhat ovate. Leaf blade tips are acuminate; bases are attenuate. 2. Leaf blade size: Mature leaves 11-12 cm long and 4 to 4.5 cm wide. 3. Petiole length: 2-3 cm. 4. Leaf margin: Ciliated and lightly serrated. 5. Leaf texture: Slightly rugose. a. Upper surface: Glabrous. b. Under surface: Glabrous. 6. Leaf color: Medium green with reddish midvein on proximal half of the leaf blade. a. Upper surface: Between 146A and 147A. b. Under surface: Greyed green, between 191A and 191B. 7. Venation: Pinnate.

Flowering description:

- A. Flowering habits.—Very floriferous. Flowering is continuous. Flowers develop progressively around the whorl of leaves, taking 5-7 days from

buds which show color, to bloom. Flowers are single and large, lasting for 2-3 weeks.

B. *Natural flowering season.*—Flowering is indeterminate and occurs throughout the year. Quantity of flowers increases with increasing light intensity and duration. However, floriferousness may wane during hot summer days in temperate climates. 5

C. *Flower buds.*—Ellipsoidal and covered with 3 sepals plus 2 rudimentary sepals fused into the 10 under surface of the superior petal. A spur originates from the base of the inferior sepal. Spur is red and approximately 5.5 cm. long.

D. *Flowers borne.*—Singly, on reddish pedicels 6 to 15 6.5 cm long.

E. *Quantity of flowers.*—One flower per leaf. Flowers occur progressively around the whorl of leaves so that tight buds to mature flowers are visible at the same time.

F. *Petals.*—Petals open nearly perpendicular to the 20 pedicel so the plane of the flower surface is nearly flat. 1. Number of petals: Five (5) petals, all overlapping. 2. Shape: All petals are heart-shaped. Superior petal has a broad base. Other

petals have a pointed base. 3. Color: Bright orange. a. Upper surface: Between 33A and 33B. b. Under surface: Between 33A and 33B. 4. Flower size: Approximately 6 cm in maximum diameter.

G. *Reproductive organs.*—Flowers are monoecious.

1. Stamens: Five (5), broad and fused to form a tube around the ovary; tinged orange red. 2. Anther: Hooded and cream colored. 3. Pollen: Cream colored. 4. Stigma: Five pointed star, colorless. 5. Styles: Very short. 6. Ovary: 5-celled, 4-5 mm long until fertilized. Grows to 1 cm or longer after fertilization; green.

Resistance to disease: Good resistance to common stem and root disease, *Rizoctonia* and *Pythium*. *Botrytis* may be a problem in humid or mist propagation environments, but no greater than with other New Guinea *impatiens* cultivars.

I claim:

1. A new and distinct cultivar of *impatiens* plant named *Barbados*, as illustrated and described.
